[57] CLAIM

The ornamental design for a lighting fixture, as shown and described.

DESCRIPTION

FIG. 1 is a perspective view taken from beneath the lighting fixture;

FIG. 2 is a side elevational view of the lighting fixture, the opposite side being a mirror image;

FIG. 3 is a bottom plan view of the lighting fixture;

FIG. 4 is a top plan view of the lighting fixture; and,

FIG. 5 is an end elevational view of the lighting fixture, the opposite end being a mirror image.

The broken lines are shown for illustrative purposes only and form no part of the claimed design.
